UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

COVER-SEAL.

1,295,032.

Specification of Letters Patent. Patented Feb. 18, 1919.

Application filed April 4, 1914. Serial No. 829,468.

To all whom it may concern:

Be it known that I, JOHN M. HOTHERSALL, a citizen of the United States, residing in Brooklyn, in the county of Kings and State 5 of New York, have invented a new and useful Improvement in Cover-Seals, of which the following is a specification.

This invention relates to improvements in cover seals and more particularly to 10 cover seals for small boxes such as are adapted to contain pills and the like.

An object of the invention is to provide a seal so arranged that it will securely hold the cover of the can or box in place during 15 shipment and prevent tampering with the contents of the box before reaching the user.

Another object of the invention is to provide a seal such as above outlined which may be easily broken by the user.

20 The invention furthermore consists in the parts and devices and in the novel combinations of the parts and devices herein shown, described or claimed.

In the drawing forming a part of this 25 specification Figure 1 is a perspective view of a box and seal showing one embodiment of my improvement. Fig. 2 is an enlarged transverse section taken substantially on the line 2—2 of Fig. 1, and Fig. 3 is a detail 30 sectional view upon an enlarged scale showing more particularly the form of the sealing strip.

In said drawing, the type of box shown is that of one having a body member 10 and a 35 sliding cover 11, the cover having depending sides 12 which slide over the sides of the body of the box, said sides 12 each having an inturned flange 13 which extends under the bottom of the body 10. To hold the 40 cover in place and to prevent tampering with the contents of the box until the same reaches the consumer, I provide a sealing strip 14 which may be made of sheet metal substantially channel shape in cross-section 45 as shown in Fig. 3 so that the upper flange 15 extends over the top of the box and the lower flange 16 extends under the box. This strip is made continuous by having the ends lapped and soldered as at 17. To facilitate 50 removal of the sealing strip, a tearing tongue 18 is provided which is formed integral with said strip and is preferably

located at one corner of the box and extended over the top thereof as shown at Fig. 1. The strip is scored as indicated at 55 19 so that when the user pulls the tongue 18 the strip will be torn at the corner and the strip then removed from the box. To facilitate the user obtaining a firm grip on the tongue 18, the latter may be provided 60 with a bead 20.

From the foregoing description the manner of using my improvements will be obvious and the construction is such that the sealing strip can not be tampered with 65 or removed without leaving evidence thereof.

Although I have herein shown and described what I now consider the preferred embodiment of my improvements, yet it will be understood that various changes and 70 modifications may be made without departing from the spirit of the invention, and all such changes and modifications are contemplated as come within the scope of the claims appended hereto. 75

I claim:

1. An article of manufacture comprising, in combination: a body member; a cover slidably united to the body member; a continuous sheet metal sealing strip of substantially channel shape in cross-section 80 entirely encircling the cover and the under side of the edge of the body member and passing across the end edges of the slidable cover flanges and across the ends of the body; and a tearing tongue formed integral with the strip, the strip being scored adjacent the tongue to facilitate the tearing. 85

2. An article of manufacture of the character described comprising, in combination: 90 a box body provided with two longitudinal recesses along the side edges of the bottom thereof; a sliding cover provided with vertical side flanges adapted to fit over the sides of said box body, said side flanges terminating in horizontal inwardly extending bottom flanges adapted to fit within the said longitudinal recesses in the bottom of said box body; and a continuous sheet metal sealing strip separate from said body and cover 95 and of substantially channel shape in cross-section having a vertical flange terminating in an upper inwardly extending horizontal flange fitting over the top of said box body 100

2
and cover, and a lower inwardly extending horizontal flange fitting beneath the bottom of said box body and cover, said continuous sealing strip having a tearing tongue by 5 which said seal may be broken to permit the cover to be removed; substantially as specified.

Signed this 28th day of March, 1914, in the presence of two witnesses.

JOHN M. HOTHERSALL.
